By *Wm. B. Stevens, Jr.*

UNITED STATES PATENT OFFICE.

CHARLES W. LASHER, JR., OF WILMETTE, ILLINOIS, ASSIGNOR TO MILWAUKEE PRINTING COMPANY, OF MILWAUKEE, WISCONSIN.

ADVERTISING DISPLAY STAND.

Application filed May 4, 1927, Serial No. 188,740. Renewed April 8, 1929.

My invention relates to articles for displaying posters and light merchandise in show cases, store windows and the like, and my main object is to provide a novel display stand which is exceedingly simple, yet amply strong for supporting purposes.

A further object of the invention is to build the novel display along stable lines, to maintain its position when weighted.

10 A still further object is to design the display stand from a single blank of sheet material, from which it is erected without the employment of accessory parts or fastening devices.

15 Another object is to combine with the novel stand an advertising card or poster, used alone or with a display of the goods or containers thereof.

A final but nevertheless important object 20 of the invention is to so construct the novel stand that it has ample bearing and self-retaining properties to maintain its shape under all conditions.

With the above objects in view and any 25 others that may suggest themselves from the specification and claims to follow, a better understanding of the invention may be gained by reference to the accompanying drawings, in which—

30 Figure 1 is a side elevation, partly broken away, of the novel display stand as mounted on a pedestal and supporting an advertising card;

Fig. 2 is a perspective view of the article 35 minus the pedestal, but indicating by dotted lines the manner in which the advertising card is applied;

Fig. 3 is a plan view of the blank from 40 which the display stand is formed;

Fig. 4 is an elevation of the advertising card, on a reduced scale;

Fig. 5 is a section of a detail, taken on the line 5—5 of Fig. 2, and using full lines; and

45 Figs. 6 and 7 are modified forms of the display stand.

Referring specifically to the drawings, the novel display stand is cut from a sheet of stiff cardboard, and folded on the dotted lines indicated in Figure 3. The medial portion 10 forms the bottom and from the sides of the same are bent upwardly the side walls 11 and 11^a. The bottom increases gradually in width toward its front end, and is continued therefrom with consecutive sections 12, 13

and 14. Adjacent their front ends, the side 55 walls 11 and 11^a, which are generally of triangular form, are formed with projections 15; and the frontal edges of the said walls are slightly recessed adjacent the projections, as indicated at 11^b. The section 14 is laterally 60 extended with tabs 16. The side wall 11 is extended rearwardly with a rectangular section 17, which is further extended with a short section 18, and terminated with a tab 19. The side wall 11^a is cut with a transverse 65 slit 20 near its rear end, and extended therefrom with a rectangular section 21; and both side walls are cut with diagonal slits 22 near their front ends.

In setting up the novel display stand, the 70 side walls 11 and 11^a are bent up to vertical position; the section 21 is bent in to form a rear wall; the section 17 is bent likewise to double the section 21; the extension 18 is bent forward to line the corner of the section 21 75 with the side wall 11^a; and the tab 19 is inserted through the slit 20 to lock the assembly and complete the rear portion of the stand.

To set up the fore part of the stand, it 80 should first be noted that the projections 15 of the side walls form a step and are used as such to guide and support the sections 12, 13, and 14. Thus, the section 12 is bent up along the front of the step; the section 13 is 85 bent down to seat upon the step, and the section 14 is bent up to seat in the recesses 11^b of the inclined frontal edges of the side walls 11 and 11^a so as to be flush therewith. The tabs 16 are now bent back upon the outside 90 of these walls and inserted through the slits 22 to lock the forepart of the stand together.

The display stand is now ready for use, and it may be placed on a flat surface, such as on a counter or show case shelf, or mounted on 95 a pedestal 23, in which case the bottom 10 is cut with an opening 24 to fit the top stud 23^a of the pedestal. A carton or other container which presents advertising value may be mounted to rest on the shelf formed by the 100 section 13 and receive the section 14 and the frontal edges of the side walls as backing supports. Resting in inclined position, the container remains stable in case of vibration or out-of-level position of the stand. Instead 105 of a container, or behind one, an advertising display card 25 may be mounted on the stand, the same leaning upon the frontal edges of

the side walls and against the section 14 and being kept from lateral displacement by being extended at the bottom with spaced tongues 26, between which the card straddles 5 the shelf 13. The card is locked to the stand by being cut with a tongue 25^a, which is inserted behind the section 14, as shown in Figure 5 and holds the card to the stand. The tongue 25^a and the section 14 are thus cooperating elements of the locking device, and render the card and the stand a unit which is rigid and stable.

It will be seen that the novel display stand is built to seat squarely upon its supporting 15 surface; and its doubled back makes it sufficiently firm to hold its shape and support articles of ample weight—such as filled containers—within reasonable limits. The frontal section 14 acts as a binding strap to 20 keep the side walls from spreading, and this property is augmented by the pressure of the article supported, which prevents the section 14 from receding and weakening the hold of the locking tabs 16.

25 Figure 6 illustrates a modification of the stand, in which the bottom tapers to a point toward the rear, and the side walls converge correspondingly to lend the article the general formation of a triangular pyramid. 30 This structure may be employed for smaller articles, and where less stability is not objectionable.

35 Figure 7 illustrates another modification in which the frontal binder 14 and the locking feature in connection therewith are eliminated, the shelf 13 being slotted at 27 to receive the frontal portions of the side walls and check spreading or collapsing tendencies 40 thereof. This modification is desirable when simplicity of construction is considered.

I claim:—

1. A display stand of sheet material having a bottom, sides formed integral with and rising from opposite side edges of the bottom, a back formed integral with one of said sides, and a front rising from the frontal edge of said bottom and stepped to form an article-supporting shelf, said front being locked with said sides.

50 2. A displayed stand of sheet material having a bottom, sides integral with and rising from opposite side edges of the bottom, a back formed by overlapped extensions of portions of said sides, and a front rising from 55 the frontal edge of said bottom and stepped to form an article-supporting shelf, said front being locked with said sides.

60 3. A display stand of sheet material having a bottom, sides formed integral with and rising from opposite side edges of the bottom, a back formed by overlapped extensions of said sides, means carried by one of said extensions and the side adjacent thereto to lock the back in position, and a front rising

from the frontal edge of said bottom and stepped to form an article-supporting shelf.

65 4. A display stand of sheet material having a bottom, sides integral with and formed by bending up portions from opposite side edges of the bottom, a back formed by overlapped integral extensions of said sides, a tongue carried by one of said extensions and insertible in a slit in the side adjacent to such extension to lock the back in position, and a front rising from the frontal edge of said bottom and stepped to form an article-supporting shelf.

70 5. A blank designed for formation into a display rack, comprising a bottom the edges of which form a geometrical figure with converging side edges, side portions bendable upward from the side edges, and back portions integral with and bendable laterally from said side portions when bent up to form a back, the edges of the side portions being inclined forwardly and formed adjacent the front with notches, and a front portion integral with the bottom and bendable up against the forward portions of the side portions and into said notches and means for securing the parts in set up relation to each other.

75 6. A display stand of sheet material, including the combination with a bottom, of side members interlocked with each other rising upwardly integrally from the bottom and having front margins sloping upwardly and rearwardly with stepped portions correspondingly spaced from the bottom, and a frontal panel integral with the bottom and folded to conform to the stepped margins of the sides to form a shelf.

80 7. A display stand of sheet material, including the combination with a bottom of side members interlocked with each other rising upwardly integrally from the bottom and having front margins sloping upwardly and rearwardly with stepped portions correspondingly spaced from the bottom, and a frontal panel integral with the bottom folded 95 to conform to the stepped margins of the sides to form a shelf and interlocked with the side members.

85 8. A display stand of sheet material, including the combination with a bottom, of slotted side members interlocked with each other and rising upwardly integrally from the bottom and having front margins sloping upwardly and rearwardly with stepped portions correspondingly spaced from the bottom, and a frontal panel integral with the bottom and folded to conform to the stepped margins of the sides to form a shelf and interlocked with the side members.

90 In testimony whereof I affix my signature.

CHARLES W. LASHER, JR.
